CLAIM

The ornamental design for an implement for picking up pine cones or the like, as shown and described.

DESCRIPTION

FIG. 1 is a perspective view of an implement for picking up pine cones or the like showing my new design; FIG. 2 is a front elevational view thereof;

FIG. 3 is a side elevational view thereof, the opposite side being a mirror image of that shown;

FIG. 4 is an end elevational view thereof; and

FIG. 5 is a rear elevational view thereof.
